CLAIM

The ornamental design for an apparatus for maintaining a dry field during dental procedures, as shown and described.

DESCRIPTION

FIG. 1 is a front perspective view of an apparatus showing my new design.

FIG. 2 is a top plan view thereof.

FIG. 3 is a right side elevational view thereof, with the left side elevational view being a mirror image of FIG. 3.

FIG. 4 is front elevational view thereof.

FIG. 5 is a rear elevational view thereof; and,

FIG. 6 is a bottom plan view thereof.
